UNITED STATES PATENT OFFICE

145,145

DESIGN FOR AN AIRPLANE

Kermit R. Riegel, Mount Rainier, Md.

Application November 29, 1945, Serial No. 124,205

Term of patent 14 years

(Cl. D71—1)

To all whom it may concern:

Be it known that I, Kermit R. Riegel, a citizen of the United States of America, residing at Mount Rainier, in the county of Prince Georges and State of Maryland, have invented a new, original, and ornamental Design for an Airplane, of which the following is a specification, reference being had to the accompanying drawings, forming a part thereof wherein:

Figure 1 is a perspective view of an airplane showing my new design.

Figure 2 is a top plan view.

Figure 3 is a front elevational view.

Figure 4 is a rear elevational view.

Figure 5 is a sectional view taken on the line 5—5 of Figure 2.

Figure 6 is a side elevational view.

I claim:

The ornamental design for an airplane, as shown.

KERMIT R. RIEGEL.
